UNITED STATES PATENT OFFICE.

EDGAR GASH, OF MACOMB, ILLINOIS.

DESIGN FOR A BADGE.

SPECIFICATION forming part of Design No. 21,758, dated August 9, 1892.

Application filed June 13, 1892. Serial No. 436,588. Term of patent 7 years.

To all whom it may concern:

Be it known that I, EDGAR GASH, a citizen of the United States, residing at Macomb, in the county of McDonough and State of Illinois, have invented a new and original Design for a Badge, of which the following is a specification, reference being had to the accompanying drawings, showing a part thereof, in which—

10 Figure 1 is a front elevation showing the shape and ornamentation of the design. Fig. 2 is a sectional elevation of Fig. 1, these two views being deemed all that is necessary to fully illustrate my new design, which consists

of a shield having the stars and bars and at 15 the upper end between the crescent curves is a representation of a broom integral therewith. On the face of the shield are placed two portrait-frames α α , which are represented as connected by the chain s .

Having thus described my new design, what I claim is—

The design for a badge, as herein described and shown.

EDGAR GASH.
